(57) **CLAIM**

The ornamental design for a combined food preservation canister and filter, as shown and described.

DESCRIPTION

FIG. 1 is a top perspective view of a combined food preservation cannister and filter showing our new design;

FIG. 2 is a top perspective view of the filter of the combined food preservation cannister;

FIG. 3 is a top view of the filter of the combined food preservation cannister;

FIG. 4 is a front view of the filter of the combined food preservation cannister;

FIG. 5 is a back view of the filter of the combined food preservation cannister;

FIG. 6 is a bottom view of the filter of the combined food preservation cannister;

FIG. 7 is a right side view of the filter of the combined food preservation cannister;

FIG. 8 is a left side view of the filter of the combined food preservation cannister;

FIG. 9 is a top perspective view of the lid of the combined food preservation cannister;

FIG. 10 is a top view of the lid of the combined food preservation cannister;

FIG. 11 is a front view of the lid of the combined food preservation cannister;

FIG. 12 is a bottom view of the lid of the combined food preservation cannister;

FIG. 13 is a top perspective view of the base of the combined food preservation cannister;

FIG. 14 is a top view of the base of the combined food preservation cannister;

FIG. 15 is a front view of the base of the combined food preservation cannister; and,

FIG. 16 is a bottom view of the base of the combined food preservation cannister.

The filter, lid and bottom portion are shown separately for clarity of illustration.
